UNITED STATES PATENT OFFICE.

NORMAN S. VAN SANT, OF PHILADELPHIA, PENNSYLVANIA, ASSIGNOR TO MERGEN-THALER LINOTYPE COMPANY, A CORPORATION OF NEW YORK.

BORDER-RULE.

1,079,078.

Specification of Letters Patent. Patented Nov. 18, 1913.

Application filed December 30, 1911. Serial No. 668,597.

To all whom it may concern:

Be it known that I, NORMAN S. VAN SANT, a citizen of the United States, and a resident of Philadelphia, county of Philadelphia, and State of Pennsylvania, have invented a new and useful Improvement in Border-Rules, of which the following is a specification.

My invention has reference to what are known as border rules, for printing plain and ornamental borders around advertisements, book pages, etc. It is now a common practice to employ for this purpose type metal slugs or rules having a longitudinal border thereon, these slugs being arranged at right angles to one another, with their ends joined to form the corners of the border. In practice much difficulty is encountered in joining and confining the ends in such manner as to produces a close joint and an unbroken border. To overcome this difficulty I construct a printing slug or rule having a border printing surface extending lengthwise thereon and turned at right angles at one end, to meet the end of the border on the adjoining slug, each slug being recessed at the end where the border is turned to form a shoulder or surface to locate and hold in position the end of the abutting slug.

The essence of the invention lies in providing slugs of the character described with locating shoulders or surfaces to hold the abutting slugs in the proper relation. It is manifest that the design of the border may be modified at will, and that the interlocking surfaces may be modified provided they have essentially the same mode of action as that described herein and shown in the accompanying drawings.

In practice I propose to cast my slug in a line casting machine of the Mergenthaler type, in a mold having a form corresponding to that of the slug, and against a matrix or matrices having a border design therein.

In the drawings: Figure 1 is a perspective view of one of my border slugs. Figure 2 is a plan view of two abutting slugs.

Referring to the drawings: A represents the body of a slug of uniform thickness except at one end, and of type height. It has along the upper edge a raised border a , extending in a straight line to one end, but at the opposite end turned at right angles.

The border design herein consists simply of two parallel lines, which at one end of the slug are turned at right angles in order to meet the corresponding border on the abutting slug. At the end where the border is turned the slug is cut away and reduced to one-half of its thickness, more or less, to leave a shoulder a' , this shoulder being located from the end a distance equal to the thickness of the slug.

In forming a box border four slugs are arranged at right angles to each other, the thick end of one slug being seated in the recessed end of the next, and against the shoulder a' , in the manner shown in the drawings. It will be seen that the shoulder is so located and the border so formed that the curved or bent ends of the border on one slug will join closely with, and form a continuation of, the border on the abutting slug, so that a continuous unbroken border is formed. The slugs may be produced in the first instance of any length and then sawed or cut to the length required for use, the shouldered end being always retained. When very large borders are to be formed two or more slugs may be joined end to end in a common line. The slugs in the middle, if any, may be made without shoulders.

Having described my invention, what I claim is:

1. A border rule provided on its edge with a printing surface to form one side of a border and turned at its end to form the corner of said border, the said rule being recessed in its side face adjacent to the turned end of the printing surface to receive the end of another slug.

2. A border rule square at one end and recessed at its other end and formed on its upper edge with a printing surface turned at right angles at the recessed end and terminating at the bottom of the recess.

In testimony whereof I hereunto set my hand this twenty-sixth day of December, 1911, in the presence of two attesting witnesses.

NORMAN S. VAN SANT.
